DESIGN FOR A JEWELLED ALPHABET

Jacques H. Leff, New York, N. Y.

Application July 30, 1940, Serial No. 94,049

Term of patent 7 years

To all whom it may concern:

Be it known that I, Jacques H. Leff, a citizen of the United States of America, residing in New York, county of New York, and State of New York, have invented a new, original, and ornamental Design for a Jeweled Alphabet, of which the following is a specification, reference being had to the accompanying drawing, forming part thereof.

Fig. 1 is a plan view of a jeweled alphabet showing my new design;

Fig. 2 is a perspective view of one of the letters of the jeweled alphabet, namely the latter A.

I claim:

The ornamental design for a jeweled alphabet, substantially as shown.

JACQUES H. LEFF.
